UNITED STATES PATENT OFFICE.

CHARLES G. SMITH, OF DETROIT, MICHIGAN.

DESIGN FOR A PATTERN FOR WIRE FABRIC.

SPECIFICATION forming part of Design No. 28,624, dated May 10, 1898.

Application filed November 23, 1897. Serial No. 659,637. Term of patent 14 years.

To all whom it may concern:

Be it known that I, CHARLES G. SMITH, a citizen of the United States, residing at Detroit, in the county of Wayne and State of Michigan, have invented a new and original Design for a Pattern for Wire Fabric, of which the following is a specification.

This invention relates to a novel design for a pattern for wire fabrics intended chiefly for spring bed-bottoms, and the leading or essential feature of the design is approximately triangular-shaped meshes bounded by waved or sinuous lines and disposed in straight courses and in alternate or reverse order, as shown in the annexed drawing, which represents a pattern for wire fabric illustrating the new design.

The triangular meshes 1 are bounded by

waved or sinuous lines and are arranged in straight courses and in inverse order. Short 20 incurves 2 appear at the obtuse angles of the triangular-shaped meshes and intersect with the longitudinal wave lines separating the courses of meshes.

Having thus described the invention, what 25 is claimed as new is—

The design for a pattern for wire fabric substantially as herein shown and described.

In testimony that I claim the foregoing as my own I have hereto affixed my signature in 30 the presence of two witnesses.

CHARLES G. SMITH.

Witnesses:

JOHN H. SIGGERS,
FRANCES PEYTON SMITH.
